ATTORNEY.

UNITED STATES PATENT OFFICE.

JACOB HOFFMANN, OF CINCINNATI, OHIO.

DESIGN FOR AN EMBLEM OR SIMILAR ARTICLE.

No. 39,634.

Specification for Design.

Patented Oct. 27, 1908.

Application filed July 23, 1908. Serial No. 445,058. Term of patent 7 years.

To all whom it may concern:

Be it known that I, JACOB HOFFMANN, a citizen of the United States, residing at Cincinnati, in the county of Hamilton and State of Ohio, have invented a new, original, and ornamental Design for Emblems or Similar Articles, of which the following is a specification, reference being had to the accompanying drawing, forming part thereof.

The figure is a front elevation of the emblem, showing my new design.

I claim:

The ornamental design for an emblem, or similar article, as shown.

JACOB HOFFMANN.

Witnesses:

JOHN ELIAS JONES,
WILLIAM SCHUCHARDT.
